INVENTOR

H. MUELLER
By S. P. Graham,
attorney:

UNITED STATES PATENT OFFICE.

HIERONYMUS MUELLER, OF DECATUR, ILLINOIS.

DEVICE FOR TAPPING MAINS.

SPECIFICATION forming part of Letters Patent No. 361,021, dated April 12, 1887.

Application filed January 12, 1887. Serial No. 224,126. (No model.)

To all whom it may concern:

Be it known that I, HIERONYMUS MUELLER, of the city of Decatur, county of Macon, and State of Illinois, have invented certain new and useful Improvements in Devices for Tapping Mains, of which the following is a specification.

My invention consists in certain details of construction and combinations of parts, as hereinafter set forth and claimed, whereby a cheap, accurate, and easily-operated tapping device may be produced.

In the drawings accompanying and forming a part of this specification, Figure 1 is a side elevation of my device ready for operation. Fig. 2 represents the clamp-frame in side elevation. Fig. 3 represents the detachable jaw of the clamp-frame. Fig. 4 represents a ratchet-wrench. Fig. 5 represents a tapping-tool. Fig. 6 represents a guide-bushing in central vertical section. Fig. 7 is a view of the upper surface of the detachable jaw; and Fig. 8 is a section of the clamp-bar on dotted line *x*, Fig. 2, showing the conformation of the rigid jaw, as seen from above.

a is the clamp-bar having rigid jaw *a'* and rigid head *a''*, both at approximately right angles with the bar and extended in the same direction.

a'' are recesses in the lower outer surface of the rigid jaw.

b are laterally-projecting pins arranged in pairs at different altitudes, the individuals of each pair being directly opposed.

c is the detachable jaw, having recesses *c'* in its upper extended surface.

d is a clamp-screw used to adjust the relative position of the clamp-jaws.

e is a block provided with trunnions *f*, on which jaw *c* freely pivots.

g is a feed-screw for the tapping-tool.

h is a tapping-tool of any suitable construction.

i is a tool-guide having adjustment longitudinally on bar *a*.

k is a set-screw, by means of which the position of the tool-guide on the bar may be temporarily secured.

l is a detachable bushing in the head of the tool-guide.

m is a set-screw for retaining bushing *l* in position.

n is a ratchet-wrench, which may be of any desirable construction, provided its tool-receiving recess conforms in shape and size to the top of the tool.

o in Fig. 1 indicates by dotted lines the position of a groove in the interior surface of the sliding tool-guide *l*, both sides of said guide being provided with such grooves of a size to pass over pins *b*.

The jaws *a'* and *c* are bifurcated, as shown in Figs. 7 and 8, and are deflected in opposite directions, forming obtuse angles with vertices on a line with the tapping-tool and the feed-screw.

The drill-shafts may be either of the inner or outer diameter of ferrule *l*, the smaller size to be used when the bushing is in the head, the larger size to be used when the bushing is removed, and the arrangement making it possible to vary the shaft to approximately conform to variation in the diameter of the tap.

The block *e* rotates loosely on a plane surface of screw *d*, and block *e* is threaded to correspond to the screw-threads.

To attach my device to a main, the jaw *a'* is passed under the same and held in contact therewith, block *e* is turned upward or downward on the screw to approximately conform to the diameter of the main, the recessed end *e'* of jaw *c* is placed under suitable pins, *b*, the trunnions of block *e* are placed in recesses *a'''* of jaw *a'*, and the position of the device on the main is made secure by tightening screw *d*. The inclination of the jaws carries the center of the device on a line with the center of the main. The bifurcate conformation makes the attachment stable and permits the free operation of the tapping-tool, and the further preparatory adjustment and the operation consist of raising guide *i*, placing a tool therein, lowering the guide and tool to a suitable extent, (the grooves *o* permitting unrestricted motion in this direction,) placing the ratchet-wrench on the tool, centering the point of the feed-screw in the top of the tool, and proceeding in the customary manner by oscillating the ratchet-handle and rotating the feed-screw.

Having thus described my invention, I claim as new and desire to secure by Letters Patent—

1. A device for tapping mains, consisting

in the combination of the clamp-bar having an upper head and a lower rigid jaw, the detachable jaw adapted to be connected at one end with the clamp-bar and at the other end with the rigid jaw, and having adjustment with relation to the said rigid jaw, the sliding guide on the clamp-bar, and the feed-screw in the head, as and for the purpose set forth.

2. A device for tapping mains, consisting in the combination of the clamp-bar, the head on the upper end of the bar, the jaw on the lower end of the bar forming an obtuse angle with its vertex depressed, the detachable jaw having adjustment with relation to the rigid jaw and forming an obtuse angle with its vertex elevated, the sliding guide on the bar, and the feed-screw in the head, as and for the purpose set forth.

3. A device for tapping mains, consisting in the combination of the clamp-bar, the head on the upper end of the bar, the bifurcate jaw on the lower end of the bar forming an obtuse angle with the vertex depressed, the detachable bifurcate jaw having adjustment with relation to the rigid jaw and forming an obtuse angle with its vertex elevated, the sliding guide on the bar, and the feed-screw in the head, as and for the purpose set forth.

4. A device for tapping mains, consisting in the combination of the clamp-bar, the head, the rigid jaw, the detachable jaw, the compressing-screw, the block pivoting loosely on the upper end of the screw and provided with trunnions that furnish bearings for the detachable jaw, the threaded block on the screw, provided with trunnions that engage the extended end of the rigid jaw, the guide on the bar, and the feed-screw in the head, as and for the purpose set forth.

5. A device for tapping mains, consisting in the combination of the clamp-bar, the head, the removable bushing in the head, the rigid jaw, the detachable jaw, the compressing-screw, the block pivoting loosely on the upper end of the screw, and provided with trunnions that furnish bearings for the detachable jaw, the threaded block on the screw provided with trunnions that engage the extended end of the rigid jaw, the guide on the bar, and the feed-screw in the head, as and for the purpose set forth.

HIERONYMUS MUELLER.
